UNITED STATES PATENT OFFICE.

HAZEL CLARK HIPOLITO, OF LOS ANGELES, CALIFORNIA.

SCREEN HANGER.

1,411,784.

Specification of Letters Patent. Patented Apr. 4, 1922.

Application filed July 25, 1916. Serial No. 111,248.

To all whom it may concern:

Be it known that I, HAZEL CLARK HIPOLITO, a citizen of the United States, residing at Los Angeles, in the county of Los Angeles and State of California, have invented a new and useful Improvement in Screen Hangers, of which the following is a specification.

This invention relates to improvements in a screen hanger described in the application of David E. Hipolito, now deceased, Serial No. 567308, filed June 16, 1910, wherein is shown a bracket consisting of a flat plate having a main body, an upwardly and outwardly projecting supporting arm having a notch in its base at its upper edge and a retaining arm extending over the plate and having a notch in its under edge above the level of the notched base of the supporting arm; said supporting arm extending above the level of the under edge of the retaining arm; said bracket being applicable to either side of a window opening so that the bracket does not have to be made in two forms for rights and lefts.

The present invention relates to a hanger adapted for use with a bracket member such as just described, and appertains particularly to a pintle member adapted to be constructed as a mate to such a bracket member.

An object of the invention is to provide a novel and superior pintle member of extreme simplicity, lightness, strength and cheapness which is adapted to co-operate with the bracket member shown in said patent application.

An important object of this invention is to form the pintle member, including a round smooth pintle and a single flat-attaching body from one form of stamping instead of constructing the pintle member of a socketed flat fastening body and a driven-in peg as in the original invention shown in application, Serial No. 567308; and this object is attained in all of the forms herein shown whether in right and left forms, in duplex pintle form or in the form so bent as to do away with the rights and lefts as hereinafter more fully set forth.

An object of the invention is to provide a light, cheap, easily constructed and easily applied hanger that is not only adapted for hanging window screens, but also for hanging a single window sash in small windows,

where, instead of a stationary or casement window the sash may be hung in place like a screen and fastened just as securely yet allowing the sash to be taken out for washing.

An important feature of this whole invention as shown in said application of David E. Hipolito and also as shown herein is to provide for fitting and hanging the screen from inside the building so as to avoid loss of time, and to minimize the labor and inconvenience of fitting and hanging the screens, and also to insure greater safety for the workingman in case of screens or windows above the first story.

It is understood that the hanger may be applied to any situation and use for which it may be adapted.

Said hanger for hanging a window screen requires two sets of hinge-like mates or members and includes two of said bracket members and two pintle members. The pintle members in said application, unlike the bracket members, are constructed as rights and lefts. An object of the invention in one of its forms is to construct all the pintle members from one form of stamping and to avoid the necessity of constructing the pintle members as rights and lefts.

Although this new hanger member is preferably made of sheet metal bent to form a reinforcement and lateral pintle, I do not limit it to the bent sheet metal construction for it may be simulated by a malleable casting in which a cylindrical edge extension of a flat attaching body constitutes a pintle to catch on and rotate in the hanger bracket, and such casting may also have the reinforcement alined with said lateral cylindrical edge extension. It is not necessary to illustrate all the forms nor the materials of the embodiment of this invention.

An object of the invention is to make provision whereby a workman standing inside a building can easily hang a screen without any gaging, countersinking or mortising, and which can be thus used on recessed effects in brick or concrete building as well as on flush surfaces and whereby, when the screen is mounted, it is easily removable by a person inside the building and is easily replaced in like manner.

An important feature of the invention in this respect is found in the specific construction of the pintle member wherein the pintle

is held with its axis practically in the same plane with the flat face of the frame to which it is attached.

Other objects, advantages and features of invention, may appear from the accompanying drawings, the subjoined detail description and the appended claims.

The accompanying drawings illustrate the invention.

10 Figure 1 is a perspective view of a hanger constructed in accordance with this invention in two forms and assembled and applied to a window screen, which is shown mounted in a building and swung partly open. The building is broken to contract the view and to expose parts that would otherwise be hidden.

Fig. 2 is an enlarged perspective view of the pintle members of the hanger detached.

20 Fig. 3 is an edge view of said pintle members.

Fig. 4 is a side view of a stamping from which either of said pintle members may be struck.

25 Fig. 5 is an enlarged perspective view of a pintle member attached to a screen, a fragment of which is shown.

Fig. 6 is a view of the right and left form of pintle member that may be struck from the stamping shown in Fig. 4.

30 Fig. 7 is a bottom view of one of the pintle members shown in Fig. 6.

Fig. 8 is a bottom view of a duplex-pintle form of the pintle member.

35 Fig. 9 is a side elevation of the pintle member shown in Fig. 8.

Fig. 10 is a side view of a stamping from which the form of duplex pintle member shown in Figs. 8 and 9 may be struck or bent up.

40 Each pintle member of the hanger comprises a sheet metal plate having a single flat body or attaching portion 1 and being widened at one end to form an integral edge extension 2; the portion of the plate adjacent the extension being bent to form a rib or lip 3 and the edge extension 2 of the widened part of said body being bent into approximately cylindrical form to constitute the terminal pintle 2'.

45 The rib or lip 3 constitutes a stiffening reinforcement for the plate adjacent the pintle 2' and also affords a projection to be tapped by the hammer of the workman for the purpose, sometimes of adjusting the pintle members on inside screens as hereinafter particularly set forth.

50 Said rib and the flat unbent portion or body 1 afford together a strong support and brace for the pintle constituted by the cylindrically bent edge extension 2'.

55 The flat body 1 is virtually in the same plane as, or radial to the produced axis of the cylindrical pintle extension 2', and is adapted to be fastened to a screen frame

or other body and is shown perforated to receive fastening means; said flat body or plate being longitudinally slotted at 5 for the reception of an adjusting pin or screw 6 and perforated with the end hole 7 to receive the fastening pin 9, which may be a screw, a nail or a tack.

The perforations are preferably alined with each other at the mid-width of the platebody 1, so that the fastening means 6 and 9 can have maximum efficiency to hold the plate when said means are fully driven into the screen frame 10.

60 In practical manufacture, stampings of the character shown in Fig. 4 are struck from some suitable sheet material such as sheet steel having a desired thickness; and the broader end is bent over and the portion 2 is bent into cylindrical form. The body 1 is made practically radial to the produced axis of the pintle in the form shown in Figs. 2—5, and at the right of Fig. 1.

65 In the form shown in Fig. 6 some of the stampings are turned over at the broader portion in one direction to form a projection 3' on one side of the plate 1 and the other stampings are turned over at the broader portion in the other direction to form such projection on the other side of the plate, thus forming rights and lefts.

70 The edge extension 2 of each pintle member is preferably spun to a cylindrical form substantially shown at 2' in Figs. 1, 2, 3, 5, 6, 7, 8 and 9.

75 In the operation of spinning or bending the pintle into cylindrical form the metal is swaged or bent gradually aslant from the rib or lip 3 to the pintle 2 as indicated at 11, thus adding to the rigidity of the pintle member. By the means stated a practically strong screen hanger or hinge is made from sheet metal of comparatively light weight.

80 The pintle members shown in Fig. 6 must be assembled in pairs as they are rights and lefts and it requires a pair for each hinge. The hinge is completed by adding to said pair two bracket members 4 of the character set forth in the patent application hereinbefore referred to.

85 In the form shown in Figs. 2, 3, 5, 8 and 9 the pintle members may be applied to either side of the screen and there is no need of selecting or pairing the parts.

90 In practical use the workman will first apply the bracket members 4 of a hanger to the sides of the opening into which the screen is to be hung, and will fasten said bracket members in place against the sides of said opening, and then he will apply the two pintle members of the hanger to the screen or other frame 10 to be hung in said opening and will adjustably fasten each of said pintle members by a pin that may

be a screw 6 inserted through the slot 5 about centrally of the body 1.

When both of the pintle members have thus been applied to the frame and adjustably secured thereon by the screw 6 the workman inside, who, by using the hanger, is enabled to do the work by fitting the screen from inside the building, can put the screen through the opening and while holding the screen can readily place the pintle members in the appropriate position in the brackets and then close the screen and adjust it to the opening by tapping the edges of the frame above or below the screen 10 wire sheet with a hammer.

When both pintle members have thus been applied to the screen and properly adjusted, the screw 6 may be securely re-tightened and the fastened clinching screw, nail, or tack 20 9 may be driven home. Then the screen is ready to be permanently hung and pintles 2' may be inserted into the brackets 4 previously fastened to the window frame or casing in the usual way as above stated. 25 Said nails in brackets 4 may be screws or pins coated previously with cement so as to give the fastening great security against coming loose.

In the double pintle form, shown in Fig. 30 9, the pintles are in alinement with each other, the back *a* of each pintle is flat, and the added pintle will lie against the screen frame when the pintle member is in place, and will not be in the way.

35 In the form shown in Figs. 2, 3 and 5 the rib 3 or swell 12 projects slightly beyond the plane of the face of the body 1, but may be impressed into the surface of the screen when finally fastened; or if not so impressed 40 will not be obnoxious to good appearance as its protrusion from the surface of the body 1 is not great.

It is thus seen that I have provided a one-piece pivot member adapted to be fastened 45 to a screen or window frame or the like for hanging said window frame by a workman standing inside the building, said pivot member having a cylindrical pintle and the screen being easily hung without any gag- 50 ing, countersinking or mortising, and which

can be used in recessed effects in brick or concrete building as well as on flush surfaces; and furthermore when the screen and the fixture are painted at the same time with the same color, the hanger is unobtrusive 55 and practically invisible.

The screen when mounted as set forth is easily removable by a person inside the building by simply adjusting it into the position shown in Fig. 1 and then lifting it so 60 as to bring the pintles 2' out through the mouth of the bracket. The screen may be replaced with equal ease and facility as may be understood from the foregoing.

I claim:—

1. A hinge member comprising a flat body and end extensions forming pintles the extensions being cylindrical and the body being bent between the extensions to form a reinforcement.

2. A hinge member comprising a plane faced attaching body, edge extensions forming and terminating in pintles, and a reinforcement between said pintles, said pintles being cylindrical and integral with the reinforcement and in alinement with each other.

3. In a screen hanger, a flat plate one edge of which extends at right angles beyond the plate body in one or both directions and in the same plane, the extended portion and the edges of the plate between them being bent into tubular form, the middle portion being adapted to reinforce the plate, and the extended portion adapted to 80 act as pintles of a hinge.

4. In a screen hanger, a plate having one of its edges over-turned to reinforce said plate, said reinforcement extending acutely beyond the vertical edge of the plate to form 90 a tubular pintle; and a cut between the pintle and the reinforcement to allow the reinforcement to be pressed flatter than the pintle.

In testimony whereof, I have hereunto 95 set my hand at San Francisco, California, this 17th day of July, 1916.

HAZEL CLARK HIPOLITO.

In presence of—

O. M. HART,
M. SHANNON.
